UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed April 15, 1928, Serial No. 102,348. Renewed August 14, 1928.

This invention aims to provide improvements in separable fasteners.

In the drawings, which illustrate a preferred embodiment of my invention:

5 Figure 1 is a plan view of a corner of a carpet showing a plurality of dotted circles to represent the position of the underlying fastener;

10 Fig. 2 is a section on the line 2—2 of Fig. 1, the stud being shown in elevation;

Fig. 3 includes an under side and a plan view respectively of the socket before attachment to a support; and

15 Fig. 4 is an enlarged sectional view taken on the line 4—4 of Fig. 3.

Referring to the drawings, I have illustrated a fastener particularly, though not exclusively, useful for securing carpets and the like to floors of motor vehicles and the 20 like.

The socket illustrated is pressed from a single piece of metal to form an annulus having an outer flange or wall 1 extending as an 25 indent extension for an inner flange or wall 2 curved to provide a smooth rounded surface surrounding a stud-receiving aperture 3. The outer and inner walls 1 and 2 are connected at the bottom of the annulus by the web 4, as shown in Fig. 4. The annulus is 30 severed by a plurality of slits 5 extending entirely through the wall 2 and web 4 and terminating in the outer wall 1 to provide resiliency to the inner wall 2 so that it may expand and contract slightly when being 35 engaged with or disengaged from the stud 6.

The annulus is preferably secured to the carpet 7 by a plurality of prongs 8 arising from the outer wall 1. These prongs 8 pierce 40 the carpet from the under side and pass through the warp and weft threads whence they are bent outwardly and downwardly by a setting die (not shown).

When the socket is secured to the carpet 7, 45 the prongs 8 are concealed by the pile or nap of the carpet. When the carpet is pulled upwardly to separate the socket from the stud, the warp and weft threads pull tightly into the hooks provided by the outwardly bent prongs, as shown in Fig. 2.

Instead of disposing of the material between the prongs 6, I have formed therefrom a plurality of ears 9, which are preferably bent inwardly from the upper edge of the wall 1, over the annulus in a plane some-

what above the plane of the upper edge of the resilient wall 2. Thus these ears 9 rest directly against the under side of the carpet and provide relatively wide smooth surfaces between the prongs to prevent cutting of the 60 carpet. They also protect the stud-engaging portions during expansion and contraction from any possibility of interference from the warp and weft threads of the carpet. These ears positively prevent the carpet from 65 wedging between the walls 1 and 2 and interfering with the operation of the socket.

It should be noted that the prongs are located between the slits and are therefore back-supported during the setting operation 70 by a substantially rigid portion of the annulus.

The ears 9 are located at the slits 5 and therefore strengthen the outer wall 1 adjacent the ends of the slits to prevent them 75 from breaking through the wall during contraction and expansion of the inner wall 2.

The stud member 6 may be of any suitable construction, depending upon whether the floor 10 is of wood, metal or other material. 80 However, the stud shown is of substantially the same construction as more fully described in my co-pending application, Serial No. 81,862, filed January 16, 1926.

While I have shown and described one embodiment of my invention, it should be understood that I have done so merely for purposes of illustration, my invention being more fully set forth in the following claims.

I claim:

1. A fastener socket having a peripheral wall, a plurality of attaching prongs extending upwardly from said wall to secure said socket to a socket-carrying support, a stud-engaging portion extending inwardly and upwardly from the lower edge of said wall to provide a stud-engaging portion surrounding a stud-receiving aperture, said stud-engaging portion severed by a plurality of slits to permit expansion and contraction thereof 100 and a plurality of ears extending inwardly from the upper edge of the peripheral wall to provide a surface above the plane of the stud-engaging portion for engagement with the support to prevent interference between 105 the support and the stud-engaging portion during expansion and contraction thereof.

2. A fastener socket having a peripheral wall, a plurality of attaching prongs extending upwardly from said wall to secure said 110

socket to a socket-carrying support, a stud-engaging portion extending inwardly and upwardly from the lower edge of said wall to provide a stud-engaging portion surrounding a stud-receiving aperture, said stud-engaging portion severed by a plurality of slits to permit expansion and contraction thereof, and means presented between the prongs for direct contact with one side of the socket support, said means being of substantial width and extending toward the expansible and contractible stud-engaging portion of the socket.

3. A one-piece fastener socket comprising a peripheral wall continuing as an inbent extension, said inbent extension being severed by slits extending into said peripheral wall, a plurality of ears integral with the upper edge of the peripheral wall and extending transverse to the axis of the socket in a plane above the plane of the upper edge of the inbent extension and in line with the slits, and a plurality of attaching prongs extending upwardly from the peripheral wall between the ears.

4. A one-piece fastener socket comprising an annulus of substantially U-shaped channel section severed by a plurality of slits extending through the inner flange and web and extending a substantial distance into the outer flange, a plurality of attaching prongs rising from the outer flange and located between said slits and a plurality of ears bent inwardly from said outer flange above the web and inner flange, said ears formed from the material cut out between said prongs.

5. A fastener socket comprising an annulus seated directly against the under side of a socket-carrying fabric, and presenting a stud-engaging portion surrounding a stud-receiving aperture, a plurality of attaching prongs arising from said annulus and hooked into engagement with the warp and weft threads of the fabric, and a plurality of fabric-engaging portions bent inwardly from the outer edge of the annulus and extending transverse to the axis of the socket at the upper edge of the annulus.

6. A one-piece fastener socket having an upstanding wall continuing as an inbent extension, said inbent extension surrounding a stud-receiving aperture to engage the neck of a stud and a plurality of inwardly extend-

ing ears integral with the upper edge of the peripheral wall, said ears extending substantially transverse to the axis of the socket for engagement against that face of a carrying medium against which the socket is to be secured to keep the carrying medium from interfering with the action of the inbent extension and means integral with the socket for securing it to a support.

7. A fastener socket comprising an annulus of channel section adapted to seat directly against the under side of a socket-carrying fabric and presenting a stud-engaging portion surrounding a stud-receiving aperture, said stud-engaging portion being divided by a plurality of slits to provide a plurality of flexible stud-engaging jaws, a plurality of attaching prongs arising from said annulus at points opposite the said jaws, said prongs being adapted to hook into engagement with the warp and weft threads of the fabric.

8. A fastener socket having yieldable means surrounding a stud-receiving aperture for engagement with a cooperating stud, an upstanding wall surrounding said yieldable means, a plurality of attaching prongs extending upwardly from the socket and a number of support-engaging ears extending inwardly from the upper edge of said wall between said prongs to provide relatively wide smooth surfaces for engagement against one face of a support to prevent cutting thereof.

9. A fastener socket installation including an annulus seated directly against the under side of a socket-carrying medium and having yieldable stud-engaging means surrounding a stud-receiving aperture and an upstanding peripheral wall surrounding said yieldable stud-engaging means, a plurality of attaching prongs arising from said annular wall and hooked into engagement with the carrying medium and a plurality of carrying medium engaging ears bent inwardly from the free edge of the annular wall, said ears being located between the attaching prongs and extending substantially transverse to the axis of the socket at the upper edge of the annulus to prevent cutting of the carrying medium.

In testimony whereof, I have signed my name to this specification.

FRED S. CARR.
